WINDING MACHINE

Charles H. Jones, Warwick, R. I., assignor to
Universal Winding Company, Boston, Mass., a
corporation of Massachusetts

Application December 12, 1940, Serial No. 369,895

12 Claims. (Cl. 242—43)

This invention relates to winding machines for winding cops, cones or packages of yarn, thread and other strand materials.

By the term "yarn" as used in the following specification and claims is meant any type of strand material whatever its characteristics, and the term "package" is used herein to indicate a wound mass whatever its shape or form.

One object of the present invention is to provide a winding machine for producing packages of generally cylindrical or conical form having the mass of yarn tapering towards its opposite ends.

Another object of the invention is to provide a winding machine for winding packages of yarn and the like with the material built up in layers of graduated length to control the shape of the package.

Another object of the invention is to provide a winding machine of the type indicated having means for depositing the yarn on the package with a varying extent of traverse changing progressively from maximum to minimum and minimum to maximum alternately throughout the winding.

Another object of the invention is to provide a winding machine of the type indicated for winding packages of the character described in my copending application, Serial No. 363,547, filed October 30, 1940.

Further objects of the invention are set forth in the following specification which describes a preferred form of construction of the winding machine, by way of example, as illustrated by the accompanying drawings. In the drawings:

Fig. 1 is a side elevational view showing two heads or units of a gang winding machine embodying the novel features of the present invention;

Fig. 2 is a plan view partly in section showing the main elements of the winding mechanism of one unit of the machine;

Fig. 3 is an enlarged detailed view of a portion of the mechanism part sectional on line 3—3 of Fig. 2;

Fig. 4 is a part sectional view of one type of package which may be wound on the present winding machine;

Fig. 5 is a diagrammatic view illustrating the variation in the length of the layers of yarn in the package as the traverse changes progressively from maximum to minimum extent and then to maximum extent alternately throughout the winding;

Fig. 6 is an enlarged plan view of a portion of

the thread-guide traversing mechanism of the machine and the former-cam or track for oscillating the thread-guide, showing the extreme positions of the guide at the end of its traverse for winding with a maximum extent of traverse;

Fig. 7 is a similar enlarged view showing the former-guide or cam-track in opposite position with the thread-guide illustrated in the positions it assumes when winding with a minimum length of traverse;

Fig. 8 is a sectional view taken on line 8—8 of Fig. 7; and

Fig. 9 is a side view showing the thread-guide and its oscillating means or cam-track.

The present invention has for its general object to provide a machine for winding packages of the type shown and described in my copending application, referred to above, in which the yarn is deposited in layers of alternately increasing and decreasing length, from minimum to maximum and maximum to minimum, throughout successive cycles. By this method of winding an improved package is produced to provide for its greater stability, to render it less subject to土壤ing in the process of winding, and to facilitate unwinding the yarn or other strand material therefrom in delivering it during subsequent transfer processes.

The present machine is particularly adapted for winding yarn or other strand material which has been sized or otherwise treated with liquid to provide a more porous structure of the yarn mass, and a disposition of the turns or convolutions of the yarn strands to avoid their adhesion in the package liable to prevent free delivery of the material in unwinding it therefrom. Such a form of package P is shown in Fig. 4 of the present drawings as being wound on a cylindrical core or tube t with a gradually increasing and diminishing length of traverse as illustrated graphically in Fig. 5. It is to be understood, however, that the present machine is adapted for adjustment to wind packages with the traverse of the yarn varying in extent in different order from that referred to above and with the yarn wound on cores or tubes of different shape, such for example, as conical holders.

Referring to Fig. 1 of the present drawings, the invention is herein illustrated as embodied in a multiple unit or gang-type machine, two winding heads or units 2 being mounted on beds 3 supported from the floor by legs 4. Each bed may mount a series of units, and as herein shown two gang machines are arranged end-for-end

and coupled together for driving by a single motor indicated at M.

Each winding unit comprises a box-like frame 5 carrying bearings for a horizontal winding spindle 6 and a cam-shaft 7 arranged therebelow in parallel relation thereto. The winding spindle 6 projects forwardly from its bearings in the frame 5 and carries thereon a suitable mandrel or holder 10 for supporting the core or cop-tube *t* on which the package is wound. The winding spindles 6 of the whole series of heads or units 2 are herein illustrated as driven from the motor M by means of an endless belt 11 engaging the peripheries of drive-pulleys 12 which may be mounted fast on the spindles or connected therewith by suitable clutches, not herein shown, as usually provided in machines of the present type. The belt 11 passes around a pulley 13 on the motor-shaft 14 and thence leads under idler-pulleys 15 and 16 to direct it across the top of the drive-pulleys 12 on the spindles 6. Preferably, a series of idler-pulleys 17 are journaled on pivoted arms 18 to adapt them to bear against the belt 11 to maintain it in contact with the pulleys 12 on the several spindles 6. An idler-pulley 17 is provided adjacent each winding unit or head 2 and the belt 11 is continuous between the drive-pulleys 12 with its slack length extending from end to end beneath the spindle drive-pulleys 12.

Referring to Fig. 2, the cam-shaft 7 of each unit carries a helical cam 20 fast thereon within the frame or casing 5; the cam-shaft being driven from the winding spindle 6 by any suitable arrangement of belt or gears as usually employed in machines of the present type but not herein illustrated. The cam 20 is formed with a helical groove engaged by a roller or bowl 22 on a reciprocable traverse-rod 23. The traverse-rod 23 is mounted to reciprocate in grooves or guideways in a traverse-frame 25 supported from the cam-shaft 7. The traverse-frame 25 has a horizontal arm 26 with a groove in which the traverse-rod 23 slides and an inclined arm 27 formed with a hub 28, see Figs. 1 and 2, surrounding the forwardly-projecting end of the cam-shaft 7 and held in place thereon by means of a disk or collar 29. The traverse-frame 25 extends outwardly from the cam-shaft 7 at an inclination to the horizontal and is held in fixed position by means of a wire rod 30 hooked through its arm 27 and terminating in a loop fastened to the side of the frame 2 by means of a screw 31. The traverse-frame 25 is preferably made in two parts with a horizontal plate-portion or traverse-frame back 32 fastened to the horizontal arm 26 of the frame by screws 33. The back 32 of the traverse-frame 25 has a groove 35 overlying and cooperating with the groove in the arm 26 to form a portion of the guideway and retain the traverse-rod in position therein.

Referring particularly to Figs. 6 to 9, inclusive, the traverse-rod 23 carries an oscillating thread-guide 40 at its outer end pivotally connected thereto by means as next described. Fastened to the end of the traverse-rod 23 is an arm or slide 41 formed from a flat strip projecting upwardly from the rod and then bent at right-angles to extend across the top of the traverse-frame back or plate 32 in spaced relation thereto. The outer end of the arm or slide 41 is bent downwardly and formed into a V-shaped catch or hook 43 engaging around the beveled edge of the traverse-frame back 32 and adapted to slide therealong. The thread-guide 40 is carried by a

mounting in the form of a bell-crank lever 45 pivoted to the arm or slide 41 by means of a stud 46. The main arm of the bell-crank lever 45 is formed at its sides with bent-over ears or lugs 47 and 48 for engaging around the sides of a hairpin-shaped portion 49 of the thread-guide 40. As herein shown the thread-guide 40 is constructed of wire bent into a relatively narrow loop 50 at its outer end, through which the yarn *y* is adapted to feed, the loop being a continuation of one arm of the hairpin-shaped loop 48 which supports the thread-guide on the bell-crank lever 45. The loop 50 of the thread-guide 40 is offset from one arm of the loop 49 by means of a sharp bend 51 and the end of the wire in the loop 50 is bent at an angle 52 to overlie this arm of the loop 49. In this way a re-entrant opening is provided for drawing the yarn strand *y* along the inclined portion 52 and between the sides of the loop 50 of the thread-guide to insert it therein, the yarn being prevented from release therefrom by the right-angular bend 51 in the wire. The hairpin loop 49 is held in connection with the lever 45 by means of an arcuately offset portion 54 on one of its arms adapted to snap into place between the two ears 47. By this construction of mounting the thread-guide 40 is adapted to rock or oscillate with the lever 45 about its pivot on the stud 46 during its reciprocation by the traverse-rod 23 whereby the extent of traverse or throw of the guide may be varied in a manner as later explained.

The means for oscillating the thread-guide 40 comprise a former-guide or cam-track 55 pivoted on a stud 56 screwed into the traverse-frame back or plate 32. The cam-track 55 is provided with a longitudinally-extending slot 57 which is engaged by a block-like shoe 60 pivotally mounted on the end of one arm of the bell-crank lever 45 by means of a pin or stud 61. The rearward end of the cam-track 55 is formed with a curved arm 62 carrying a stud or pin 63 riveted thereto and projecting upwardly through a bearing aperture in a slide-bar 65 which extends the full length of the gang-machines and is similarly connected to the cam-tracks of all the several winding units. By sliding the bar 65 the different cam-tracks 55 may be rocked on their pivots 56 to position them in variable angular relation to the plane of movement of the traverse-rod 23 and the thread-guide 40 carried thereby; two opposite extremes of position of the cam-track being represented in Figs. 6 and 7. By thus changing the position of the cam-track 55 the thread-guide 40 associated therewith is caused to be rocked or oscillated during each traverse by the sliding engagement of the shoe 60 on the bell-crank lever 45 with the slot 57 in the track.

This alteration in the angular relationship of the cam-track 55 takes place continuously throughout the winding of a package, being effected and controlled by a rotatable eccentric or cam 66 shown in Figs. 1 and 2. The cam 66 as herein illustrated is of generally heart-shape and mounted eccentrically on a spindle or shaft 67 supported in a bearing 68 on a casing or bracket 69. The shaft 67 carries a bevel gear 70 pinned to its rearward end which meshes with a pinion 71 on a shaft 72. The shaft 72 is journaled in a bearing 73 on the bracket 69 and carries a sprocket-wheel 74 fast at one end. The sprocket-wheel 74 is connected by a chain 75 to another sprocket 76 fast on a shaft 77 extending horizontally below the winding units and journaled in suitable bearings 78 and 79 carried by brackets

80 and 81 supported from the legs 4 of the machine frame.

The bracket 81 is formed with a bearing 82 in which is journaled a shaft 83 carrying a belt-pulley 84 at one end. The pulley 84 is connected by an endless belt 85 to a similar smaller pulley 86 fast with and rotatable by the idler-pulley 15, previously referred to as having the driving belt 11 passing therearound. On the shaft 83 is a worm 87 meshing with a worm-wheel 88 on the lower shaft 11. By these connections the shaft 77 is driven from the main drive of the machine and through the chain 15 and sprocket-wheels 74 and 76, it drives the shaft 72 and gears 70 and 71 to rotate the shaft 67 and cam 66. A bowl or roller 90 secured fast to the slide-bar 65 engages the periphery of the cam 66 to cause the bar to be reciprocated therefrom with a relatively slow longitudinal motion. The roller 90 is journaled on a stud 91 projecting from a bifurcated member 92 which straddles the slide-bar 65 and is clamped thereto by means of a nut 89 and washer 93 shown in detail in Fig. 3; a wire ring 94 sprung into a circumferential groove 95 at the end of the stud 91 serving to hold the roller 90 in place thereon. To maintain the roller 90 constantly bearing against the rim of the cam 66 a helical spring 96, see Fig. 1, acts to draw the bar 65 toward the left; the spring being anchored to a pin 97 fast in the frame 5 and connected at its opposite end to a member 98 fixedly clamped on the slide-bar by means of a set-screw 99.

When the machine is equipped for sizing or emulsifying the yarn as it is wound into the package a moistening device may be provided, for example in the form substantially as shown in Fig. 1 of the present drawings. As herein illustrated the moistening device comprises a trough or tank 100 for the winding units of each gang-machine. The troughs 100 are arranged below the winding heads 2, being supported from the legs 4 of the machine frames and adapted to contain the desired emulsifying liquid such as a suitable size. A horizontal shaft 101 is journaled in bearings at the ends of each trough and carries a series of rolls 102 which dip into the liquid in the tank; a chain 103 connecting the roll-shaft to be driven from the lower shaft 77 previously referred to, see Figs. 1 and 2, by means of sprockets 104 and 105. The yarn *y* is supplied from a suitable source arranged below the emulsifying device, but not herein shown, and the strand leads up through an opening in the front of the trough and is directed across the surface of the moistened roll 102 by means of a suitable guide 106. From the guide 106 the strand *y* feeds upwardly through the thread-guide 40 and is attached to the tube *t* on which it is wound by the rotation of the winding spindle 6.

The construction and arrangement of the mechanism of the present improved winding machine having been described in detail, its method of operation is explained as follows: Each head of the machine is prepared for winding by leading the strand of yarn *y* from its supply across the moistening roll 102 and through the fixed guide 106, whence it is carried up through the thread-guide 40 and its end attached to the core or tube *t* on the winding spindle 6, the tube having been placed on its mandrel or holder 10 and secured rotatively therewith. Power is applied to the spindles 6 of the gang machines from the motor M driving through the belt 11 which engages the several drive-pulleys 12 on the spin-

bles. As each spindle 6 is rotated the strand of yarn *y* is wound on the core or tube *t* and traversed back and forth longitudinally thereof by the reciprocation of the thread-guide 40 carried by the traverse-rod 23. The machine may be started to operate with the former-guide or cam-track 55 in any position in which it has remained after a previous winding operation and the initial traverse of the yarn on the tube *t* will be regulated in accordance therewith as the thread-guide is oscillated from the bell-crank lever 45 due to the travel of the shoe 60 in the slot 57 of the cam-track. For example, if the cam-track 55 has been rocked to the position illustrated in Fig. 6 after the cam 66 has been turned to the position shown in Fig. 1, the thread-guide 40 will be actuated with a maximum extent of throw and the yarn will be traversed to substantially the full length of the tube *t* shown in Fig. 4. Each time the traverse-rod 23 is carried outwardly to the full extent of its traverse the shoe 60 riding in the slot 57 of the cam-track 55 will cause the bell-crank lever 45 to rock into the position shown in Fig. 6 to move the loop 50 of the thread-guide 40 outwardly with respect to the end of the traverse-rod to increase the length of traverse of the yarn. On the other hand, as the traverse-rod 23 moves back in the reverse direction the engagement of the shoe 60 with the slot 57 in the cam-track 55 will rock the lever 45 in the opposite direction to carry the loop 50 of the thread-guide 40 rearwardly to the position indicated by dash lines in Fig. 6 whereby to extend the traverse of the yarn in this direction. As the winding continues the edge-cam 66 is rotated slowly through its connections with the main drive of the machine, that is by the rotation of the shaft 77 communicated through the sprocket 76, chain 75, and sprocket 74 to the pinion 71 and gear 70 on the shaft 67 of the cam. This slow turning motion of the cam 66 causes its eccentric edge to act against the roller 90 fast on the slide-bar 65 to slide the bar toward the right as viewed in Fig. 1. The bar 65 being connected to the cam-track 55 at 63 causes the track to be slowly shifted or rocked on its pivot 56 until eventually it assumes the position shown in Fig. 7 of the drawings. During this pivotal movement of the track 55 the inclination of its slot 57 with respect to the transverse-rod 23 will be gradually lessened so that it will have a diminishing effect to rock the bell-crank lever 45, thereby reducing the length of traverse imparted to the strand of yarn *y* being deposited on the tube *t*. As the cam-track 55 reaches a position parallel with the traverse-bar 23 the oscillating motion of the guide will cease entirely so that the yarn will be traversed to an extent equal to that of the traverse-rod. The displacement of the cam-track 55 continues, however, beyond this latter point until eventually the track reaches the position shown in Fig. 7. As the track 55 is shifted from its parallel relation to the traverse-rod 23 toward the inclined position shown in Fig. 7 its action on the bell-crank lever 45 and thread-guide 40 will be the opposite from that first described, that is it will rock the thread-guide 40 inwardly from the limits of movement of the traverse-rod to shorten the traverse imparted to the strand *y* or, in other words, it will gradually reduce the length of the layers being deposited on the package wound on the tube *t*. After the bar 65 has reached the end of its movement toward the right as indicated in Fig. 7 it is swung back in the opposite direc-

tion to increase the length of traverse of the thread-guide 40 to the maximum again and this alternate shortening and lengthening of the traverse continues in successive cycles throughout the winding of the package.

The motion imparted to the slide-bar 65 by the cam 66 is relatively slow so that the change in traverse of the yarn is gradual. However, the actuation of the slide-bar 65 is so timed that it will rock the cam-track 58 on its pivot throughout its full movement in opposite directions a sufficient number of times to provide a relatively large number of changes in the traverse of the yarn in each package. For example, it has been found that starting with the maximum extent of traverse and reducing its length gradually to the minimum, and then increasing the traverse to the maximum, this cycle if completed four times a minute when winding the yarn at a spindle speed of 1210 R. P. M. will produce a satisfactory package of the type illustrated in Fig. 4 of the present drawings. The ratio between the maximum and minimum length of traverse and the period of change in successive cycles is arbitrary, however, and may be adjusted to wind packages of different type which, in most instances, will have the same general form, that is with the periphery tapering toward the ends due to depositing more yarn at the center of the mass. Fig. 5 is a graphical representation of one preferred method of change in the traverse of the yarn from maximum to minimum extent and back to maximum extent continuously through successive cycles of the winding.

After the package is completed to the required size it is removed from the machine and the winding may be continued to produce other packages without any adjustment of the mechanism of the machine. That is to say, the winding of a package may be started at any point as regards the changing length of traverse without materially affecting the form or structure of the package produced on the machine.

It will be observed from the foregoing specification that the present invention provides a novel and ingenious winding mechanism for continuously changing the length of traverse of the yarn being wound to produce packages of improved type wherein the layers are of graduated length to secure the advantages hereinbefore set forth and stated more fully in my copending application referred to above.

While the invention is herein shown and described as embodied in a preferred form of construction, it is to be understood that modifications may be made in the structure and arrangement of the parts of the winding mechanism and the means for controlling the change in the length of traverse of the yarn during winding on the machine without departing from the spirit or scope of the invention. Therefore, without limiting myself in this respect, I claim:

1. In a winding machine, a rotary winding spindle, a traverse-rod reciprocable opposite said winding spindle, a thread-guide reciprocated by said traverse-rod and adapted to be shifted longitudinally thereof, and means for shifting said thread-guide first outwardly and then inwardly along the traverse-rod to alternately increase and diminish the length of traverse stroke of the guide continuously during the reciprocation of the traverse-rod.

2. In a winding machine, a rotary winding spindle, a reciprocable member, means to reciprocate said member, a thread-guide pivoted to

said member to adapt it to oscillate with respect thereto, and means to oscillate the thread-guide on the reciprocable member first in one direction and then in the opposite direction during its reciprocation thereby to alternately increase and diminish the length of traverse of said thread-guide at both ends of its stroke throughout the winding of a package.

3. In a winding machine, a rotary winding spindle, a member reciprocable opposite said spindle, a thread-guide pivotally mounted on said member to adapt it to oscillate with respect thereto, means for reciprocating said member, a rockable cam-track for oscillating the thread-guide continuously during its reciprocation by said member, and means for rocking the cam-track first in one direction and then in the opposite direction to alternately shorten and lengthen the traverse stroke of the thread-guide at both ends of the package being wound.

4. In a winding machine, a rotary winding spindle, a reciprocable traverse-member, a thread-guide pivotally connected to said member, a rockable cam-track, means engaging said track and operative on the thread-guide to oscillate the latter about its pivot, and means to continuously move the cam-track first in one direction and then in the opposite direction to cause it to rock the thread-guide to alternately lengthen and diminish its extent of traverse stroke at both ends of the winding spindle during the winding of a package thereon.

5. In a winding machine, a rotary winding spindle, a traverse-member reciprocable longitudinally of said spindle, a thread-guide pivotally connected to said traverse-member, a cam-track mounted on a fixed pivot to adapt it to be swung into inclined relation to the path of travel of the thread-guide, means engaging said cam-track for rocking the thread-guide on the traverse-member during its reciprocation thereby, and means for continuously swinging the cam-track back and forth on its pivot to cause it to rock the thread-guide to alternately increase and diminish its length of traverse stroke at both ends of the winding spindle.

6. In a winding machine, a rotary winding spindle, a reciprocable traverse-member, means to reciprocate said member longitudinally of the winding spindle, a thread-guide pivotally connected to the traverse-member, a cam-track pivoted to swing toward and away from the traversing member, means connected to the thread-guide and travelable on the cam-track, and means for continuously shifting the position of the cam-track first in one direction and then in the opposite direction to cause it to rock the thread-guide to progressively change its extent of traverse at both ends of its stroke from maximum to minimum and minimum to maximum in successive cycles throughout the winding.

7. In a winding machine, a rotary winding spindle, a traverse-member reciprocable longitudinally of said spindle, a thread-guide carried by said traverse-member and shiftable thereon to vary its extent of traverse during the reciprocation of said member, a cam-track operative on the thread-guide to shift the latter on the traverse-member, and means to continuously vary the position of said cam-track to shift the thread-guide first in one direction and then in the opposite direction to alternately lengthen and shorten its traverse in successive cycles

throughout the winding of a package on the winding spindle.

8. In a winding machine, a rotary winding spindle, a rockable thread-guide, means for traversing said thread-guide longitudinally of the spindle, and means for rocking the thread-guide continuously during its traverse comprising a cam-track operative on said thread-guide, and means for continuously moving the cam-track to gradually shift it from one position to another and then gradually return it to its first position to progressively increase and diminish the extent of traverse of the thread-guide at both ends of its stroke during recurring cycles in the winding.

9. In a winding machine, a rotary winding spindle, a traverse-bar reciprocable longitudinally of said spindle, means for reciprocating the traverse-bar, a thread-guide pivotally connected to said traverse-bar to adapt it to rock in the direction of its traverse, a cam-track rockably mounted on a stationary pivot, means slidable on the cam-track and connected to rock the thread-guide, and a cam for rocking the track on its pivot to vary the extent of oscillation of the thread-guide to progressively increase and diminish the extent of its traverse at both ends of its stroke during recurring cycles throughout the winding.

10. In a winding machine, a rotary winding spindle, a reciprocable traverse-member, a thread-guide pivotally connected to said traverse-member to adapt it to oscillate with respect thereto, a cam-track rockably mounted on a fixed pivot, means slidable on the cam-track and connected to the thread-guide to rock the latter during its traverse, a member connected to the

cam-track to swing it on its pivot, and a cam for sliding said member longitudinally in opposite directions to swing the cam-track on its pivot to oscillate the thread-guide to progressively lengthen and shorten its traverse at both ends of its stroke during successive cycles throughout the winding.

11. In a winding machine, a rotary winding spindle, a fixed support positioned opposite said spindle, a traverse-member reciprocable on said support, a thread-guide pivotally connected to said traverse-member to adapt it to oscillate during its reciprocation thereby, a cam-track pivoted on the fixed support, a shoe slidable on the cam-track and connected to rock the thread-guide during its reciprocation with the traverse-bar, a longitudinally-slidable bar connected to the cam-track, and a cam for sliding said bar in alternately opposite directions to swing the cam-track on its pivot during the reciprocation of the traverse-member to rock the thread-guide to progressively vary its extent of traverse.

12. In a gang winding machine, the combination with a plurality of winding units, of a rotary winding spindle for each unit, a traverse-member reciprocable longitudinally of each spindle, a rockable thread-guide reciprocable by said traverse-member, a cam-track for rocking said thread-guide during its reciprocation by the traverse-member, means connecting the cam-tracks of the several winding units to shift the position of the latter, and means for actuating said last-named means to shift the cam-tracks first in one direction and then in the opposite direction to progressively alter the range of traverse of the thread-guides.

CHARLES H. JONES.
